GARMENT HANGER

Frederic S. Shaffer, Cincinnati, Ohio

Application March 2, 1932, Serial No. 596,293

4 Claims. (Cl. 223—88)

This invention relates to garment hangers and particularly to garment hangers adapted for use by dry cleaners for returning dresses, suits, overcoats, and all types of garments to their owners after they have been cleaned and/or pressed.

5 It is the present practice of dry cleaners in returning garments to pin the shoulder straps of sleeveless evening gowns or other sleeveless garments to the hangers, likewise dresses having very wide neck openings, men's trousers, and other articles which are normally hung over the horizontal bar of the hanger. This pinning is for the purpose of preventing the garment from being shaken off the hanger by the jouncing it normally receives in the delivery wagon as it is 10 being returned to the owner. This practice of pinning requires an appreciable amount of hand labor and is injurious to the garments, produces very unsightly pinholes and is very obnoxious to the dry cleaner's patrons.

15 The object of this invention is to provide a hanger sufficiently cheap to permit its use by dry cleaners for returning garments to their patrons, which entirely eliminates the necessity of using pins to hold the garments to the hanger and which will at once take care of all of the various 20 different types of garments in relation to which the specified problem arises.

The hanger of this invention comprises a length of wire bent upon itself to form a horizontal bar, two shoulders sloping upwardly from each end thereof, and a hook portion between the top ends of said sloping shoulders. The novelty of the invention comprises a downwardly extending notch or loop in each shoulder portion, the bottom of 25 said loop being positioned sufficiently close to the horizontal bar as to constitute compression means in conjunction therewith, the bottom of said loop preferably being parallel with the horizontal bar to provide appropriate compression surface.

30 Garments of all types, evening gowns or men's trousers, draperies, neckties, etc., may be quickly and easily placed securely on these hangers as a result of this novel construction.

35 Other objects and certain advantages will be more fully apparent from a description of the accompanying drawing in which:

40 Figure 1 is a side view of the improved hanger.

45 Figure 2 is a perspective view of the hanger showing a pair of trousers supported thereon.

50 Figure 3 is a side view of the garment hanger showing a woman's undergarment supported thereon illustrating the function of the hanger for the support of a garment having shoulder straps.

The garment hanger of this invention includes a supporting means and the usual triangular garment form with the conventional provision of inclined shoulder support bars for an upper garment and a cross bar for supporting trousers. 5 It is recognized that certain garments such as women's garments having no sleeves or of wide neck opening, or in many cases thin shoulder straps, do not efficiently remain on the hanger or have a tendency to slide down the inclined support bars and to thereby become displaced from the hanger, and that displacement occurs in connection with men's trousers draped from the lower bar. For this reason, generally described, the present hanger includes a device preferably 10 integral therewith which receives and definitely prevents displacement of the particular garments.

The clamping devices are adapted to engage 15 upon the trousers for maintaining them on the lower cross bar, it being considered an additional item of value that these devices are formed as a part of the devices preventing displacement of the garments from the inclined shoulder support bars.

20 Referring specifically to the drawing, as one form of the foregoing invention, the hanger is constructed of a single piece or length of wire 5. The wire 5 is bent into triangular form to provide 25 a lower cross bar 6 and inclined or shoulder support bars 7, these inclined support bars being joined and the ends of the wire length being intertwined as at 8 and one end extended beyond 30 and bent to form a hook 9. In the formation of the inclined support or shoulder bars 7, the wire 35 is formed or looped to provide receptacles 10 having introductory slots 11 along the inclined bar lengths. Each of these receptacles, specifically 40 described, are formed by bending the wire completely reversely as at 12 practically back into the 45 particular bight 13 at the adjacent lower corner of the hanger, then extending the wire parallel with but slightly spaced from the lower bar as at 14 and then upwardly as at 15 to a point adjacent the reverse bend leaving a slot 11 of sufficient width to permit the insertion of shoulder straps 50 whereupon the further extension of the wire is as 55 previously described.

As shown in Figure 2, the trousers 16 are in 55 clamped position on the lower support or cross bar 6 of the hanger, the depending loops or enclosures 10 for the shoulder straps having their lower cross pieces 14 engaged upon the trousers and clamping the same against the lower or cross bar 6. The normal width of the slot formed be-

tween the lower bar and the depending loop is less than the thickness of the cloth. In some cases the cross bars 6 and 14 may be in contact and readily spread for the insertion of the garment or cloth article therebetween. Thereby, when the cloth is interposed, a clamping action occurs.

As shown in Figure 3, a woman's garment, such as a slip 17, is hung from the hanger by insertion of the shoulder straps 18 through the slots and into the depending loops forming the receptacle for the straps. These loops prevent undue lateral displacement of the straps and provide the strictly horizontal support bars 14 therefor.

It is also of importance that the hanger will readily support garments of thin material such as silk dresses which may have wide neck openings and will prevent displacement of these garments by virtue of the break in the inclined surfaces provided by the slots. The neck margin of a woman's garment such as a dress will depend into the slots and there will be less tendency for slippage from the inclined support bars.

Having described my invention, I claim:

- 25 1. A garment support formed of wire bent into a triangular form and including a hook at its upper end, said form providing inclined shoulder supporting bars and a lower cross support bar, the portions of wire forming the inclined support bars being bent to form depending loops of triangular form, the base portions of which provide lower cross bars disposed parallel with and spaced apart from the lower cross bar of the hanger and said loops of triangular form including entry slots at their apexes whereby the shoulder straps of garments may be inserted through the slots and supported on the lower cross bars of the loops and trousers may be interposed between the lower cross bars of the loops and the lower cross bar of the hanger form.
- 30 2. A garment support formed of wire bent into a triangular form and including a hook at its upper end, said form providing inclined shoulder

supporting bars and a lower cross support bar, the portions of wire forming the inclined support bars being bent to form depending loops having combined clamping and support bars disposed adjacent the lower cross bar of the hanger and said loops including entry slots at their tops whereby the shoulder straps of garments may be inserted through the slots and supported on the lower bars of the loops and trousers may be interposed between the lower bars of the loops and the lower cross bar of the hanger form.

3. A garment hanger of bent wire of isosceles triangular form having a hook at the apex and having sides bent inwardly and downwardly to form loops having restricted apertures, the bases 15 of which loops are formed to lie adjacent to and parallel with the base of said hanger, through which loop apertures garment straps may be disposed to rest on said loop bases for preventing escape of the garment from the hanger and over which base bar of the hanger trousers may be placed subject to the flexed pressure of said loop bases.

4. A garment hanger formed of wire bent into triangular form and comprising a support hook, 25 shoulder conforming members depending in diverging relation from said hook, a trouser support cross bar connecting said shoulder members at their diverging ends and adapted to lie in a horizontal plane when the hanger is in service 30 position, and garment hanger support loops formed as depending inward triangular shaped extensions of said divergent shoulder conforming members respectively, the loops each having a straight cross bar portion parallel with the trouser cross bar, said triangular shaped extensions providing entry slots at the apexes thereof permitting insertion of the straps of a garment therethrough for support on said straight cross bar portions.
